4 Claims. (Cl. 235—92)

1

This invention relates to counting apparatus and is a division of copending application Serial No. 534,966, filed May 10, 1944, now abandoned. Such apparatus includes a plurality of counters, each counter being utilized to count a different set of facts. The apparatus may be used wherever it is desired to provide separate counts of distinguishable items and of totals. For example, it is possible to use the apparatus for counting the number of slips or checks deposited in the different compartments of a machine, such as disclosed in Patent No. 1,946,906, or as a vote counter where each counter may be assigned to a different candidate. On the other hand, the apparatus may be conveniently provided as an attachment to a record sorting machine, where each counter may serve to count the number of occurrences of a designation on the cards or of combinations of designations or of the number of cards distributed to each sorting pocket. An instance of the latter use of counting apparatus is found in Patent No. 1,926,896.

The general object of the present invention resides in the provision of improvements in counting apparatus, leading to increased simplicity of construction and of operation and providing for much greater compactness of structure than heretofore attained. The apparatus according to the present invention may be assembled as a compact unit to be readily attached to any record handling machine or the like, or to be used as a separate unit and associated with suitable controls for the counter sets.

More specifically, an object of the invention is to provide counter sets arranged in an organization which is stationary during counting operations and in which a rotating magnet moves past the counters in succession to operate the same selectively.

Another object of the invention is to provide novel resetting means for the counter sets.

One of the objects of the invention is to provide novel, simple means for selectively actuating the counter sets.

More specifically, an object is to provide a single, differentially actuatable device for controlling operation of any of the counter sets.

The object is, moreover, to provide a single actuating mechanism for the counter sets and a single magnet for cooperatively connecting the actuating mechanism to any desired one of the counter sets.

The object is, further, to provide a single control and actuating means for a plurality of counter sets, with such means being timed syn-

chronously with control means to selectively operate the counter sets.

Other objects of the invention will be pointed out in the following description and claims and illustrated in the accompanying drawings, which disclose, by way of example, the principle of the invention and the best mode, which has been contemplated, of applying that principle.

In the drawings:

10 Fig. 1 is a general view showing the manner in which counting mechanism is coordinated with a well known type of record card sorting machine.

15 Fig. 2 is a view taken through the record card feeding mechanism of the sorting machine showing the drive connections therefrom to the counting mechanism.

20 Fig. 3 is a section taken on lines 3—3 of Fig. 2, showing the reset operating key and levers and the record tape feed devices.

25 Fig. 4 is an enlarged sectional detail showing the operating devices for the counters.

Fig. 5 is a sectional view taken substantially along lines 5—5 of Fig. 4, showing the rotating magnet and the reset gear connections.

30 Fig. 6 is a wiring diagram of the electric circuits of the machine.

In Fig. 6 the card sensing mechanism of a well known sorting machine is diagrammatically shown as comprising a sensing brush 12, between which and a contact roller 24 record cards having a column of index point positions move so that the brush senses the positions in the order 9, 8, 7, 6, etc. and the occurrence of a perforation in any such position will enable brush 12 to contact roller 24 through the perforation at the time the related position is sensed. A distributor 35 is synchronized with the movement of the card, so that its positions 9, 8, 7, 6, etc., pass stationary brushes 36a, 37a, 38a, 39a as the corresponding card positions pass brush 12. The circuit connections controlled through brush 12 and commutator 35 will be fully explained in connection with the later description of the circuit diagram.

The card feeding mechanism comprises a picker 18 (Fig. 2) horizontally reciprocable through arm 19 and link 20 connected to an arm 21 on main drive shaft 22, which makes one revolution for each card advanced. The picker advances cards from the bottom of the stack 23 to the usual feed rollers which advance them to and between brush 12 and contact roller 24 (Fig. 6).

Shaft 22 is driven by motor M (Fig. 6) which is connected to opposite current supply lines 25 and 26 through contacts R1a and R2a of motor relays R1 and R2. Relays R1 and R2 are con-

nected in parallel to line 26 and through a wire 27 to the contacts R3a of a time delay relay R3, which contacts are connected through a wire 28 to the start relay R4. Energization of relay R3 is controlled through a cold cathode tube 14 of the type OA4G through a circuit from negative line 26, cathode of the tube, anode of the tube, relay R3 to positive line 25. However, no current can be passed from cathode to anode of the tube until the starter anode reaches a potential of about 55 volts. The starter anode voltage is determined by the change in the .5 mfd. condenser 29 which is zero at the time current is supplied to main lines 25, 26, when the voltage rises across the condenser at a rate determined by the capacity of the condensers and the value of resistance S15. The charging circuit is from negative line 26, condenser 29, resistance S15, relay contacts R3b (lower), relay R3 to line 25. When the starter anode reaches the trip voltage, an arc results from cathode to starter anode, which establishes the pickup circuit from cathode to anode and contacts R3b (upper) establish a holding circuit from negative line 26, resistance S16, contacts R3b (upper), relay R3 to line 25, which maintains relay R3 energized until current is interrupted to lines 25 and 26.

Depression of the start key 30, after the time interval to energize relay R3, will cause a closure of contacts 30a to complete a circuit from line 25, normally closed contacts 31, contacts 30a, relay R4, wire 28, contacts R3a, wire 27, relays R1 and R2 in parallel to line 26. Motor M is then brought into operation and cards commence to advance from stacker 23. As they advance in succession, they engage the usual card levers generally designated 32 (shown diagrammatically in Fig. 6) and located to close contacts 32a, 32b and 32c and hold them closed as long as cards continue to feed. Contacts 32a close before the index point positions of the first card have reached brush 12, contacts 32b close after the index point positions of the first card have passed brush 12 and contacts 32c close just before the first index point positions of the first card reach brush 12. Thereafter, they all remain closed. Contacts 32a provide a holding circuit for relay R4 traceable from line 25, contacts 31, wire 40, contacts 32a, contacts 33, stop key contacts 34a, contacts R4a, relay R4, wire 28, contacts R3a, wire 27, relays R1 and R2 to line 26.

The sorter is provided with the usual distributor 35 (Figs. 1 and 6) which makes one revolution for each card cycle and is provided with a ring of twelve segments 36 electrically connected with a common conducting ring 37 and a holding segment 38. For the purposes of the present invention, and as will be explained in connection with the counting mechanism, an additional four segments 39 are provided which are also electrically connected to common conductor 37. Stationary brushes 36a, 31a, 38a and 39a traverse the like designated segments. The segments 36 contact the brush 36a at the time that the like numbered hole positions in a card column are at the brush 12. If, for example, there is a hole in the 4 position, then when this position is at brush 12 there will be a circuit completed, traceable from line 25, contacts 31, wire 40, brush 31a, common 37, connection to the 4 segment 36, brush 36a, wire 41, card lever contacts 32c, contact roller 24, 4 hole in the card, brush 12, resistance S6, contacts R5a, relay R6, resistance S1, switch 34 to line 26.

When relay R is energized, it closes its contacts

5 tacts R6a to provide a holding circuit from line 25, contacts 31, wire 40, brush 31a, common 37, segment 38, brush 38a, wire 42, relays R7, R5, contacts R6a, relay R6, resistance S1, switch 34 to line 26.

4 The mechanical construction of the counting mechanism will now be described, and thereafter the controlling circuit connections.

Referring to Fig. 2, the main sorter shaft 22 has a spur and bevel gear connection generally designated 44 with a shaft 45 and with a ratio so that the shaft 45 makes one revolution for each revolution of shaft 22. At its right hand end (Figs. 4 and 5) shaft 45 has secured thereto 10 a block or balanced arm 46 provided with an opening 47 in which there is secured a pair of magnets 48. That is, the weight of the lever 46 and magnets 48 is equally divided on opposite sides of shaft 45. The laminated cores 49 of the magnets lie in a line radial with respect to shaft 45 and, as the shaft rotates counterclockwise as viewed in Fig. 5, the ends of cores 49 pass latches 50 arranged in a circle about the shaft. There are sixteen of these latches and for each there is 15 provided a counting mechanism of the well known Veeder type. Energization of magnet 48 when it is opposite any latch 50 and as it is passing such latch will attract the same and rock it 20 clockwise (Fig. 4) about a pivot wire 51, against the tension of spring 52.

25 A limiting disk extending into a bifurcation in the latch insures that the latch will not contact the magnet core so there is no interference with the latter's rotation. In line with each latch 50 is a lever 53 normally held in the full line position shown and released to rock to its dotted line position, under the influence of spring 54 when latch 50 is attracted. This lever 53 is pivoted at 30 55 to a plunger 56 which is guided for radial reciprocation in a sleeve 57 fixed in a stationary drum 58.

35 Secured to shaft 45 is an eccentric cam 59 about which there is a sleeve 60 shouldered at 61 and, when lever 53 is held by latch 50, the inner end of the lever lies to one side of the plane of rotation of sleeve 60. Upon release of the lever, its inner end is drawn by spring 54 into the plane of the sleeve and against shoulder 61. The relative positions of magnet 48 and sleeve 60 are shown in Fig. 5, where it will be noted that, when the 40 magnet 48 is opposite a latch 50, the low portion of least radius of sleeve 60 is opposite the corresponding lever 53 and, as the sleeve continues to rotate, it will urge lever 53 outwardly and through the lever will force plunger 56 in the 45 same direction. Plunger 56 is provided with a slot 63 at its outer end in which a roller 64 of a bail 65 rides. A coil spring 66 (Fig. 5) has its inner end secured to bail 65 and its outer end to 50 stationary side plate 67 of the counter, so that as the bail is rocked clockwise as viewed in Fig. 5 the spring is tightened and later, as lever 53 rides along the periphery of sleeve 60, will restore plunger 56 to its initial position.

55 After magnet 48 has tripped latch 50 and passed on to the next latch, the first will rock back to its initial position so that later, when plunger 56 is retracted, an extension 68 thereon will strike a shoulder 69 of the latch to thereby cause the lever 53 to swing back to its initial 60 position (Fig. 4) as the plunger continues to its restored position.

65 Bail 65 has pivoted thereto the usual spring pressed actuating pawls designated 70 which cooperate with ratchets 71 secured to wheel 72 to 65 advance the lowest ordered wheel (the one far-

the left in Fig. 4) one unit for each oscillation of the bail. The usual tens transfer action is provided to cause a unit advance of a higher order, whenever the next lower order has advanced ten steps. The details of such type of counter are well known and, therefore, have not been illustrated in detail herein.

The manner in which magnet 48 is energized will now be explained in connection with the circuit diagram (Fig. 6) where a counting switch 75 is first closed if it is desired to count the occurrence of perforations. When the card sensing brush 12 makes contact through a hole in the card in any of the successively sensed positions 9, 8, 7, 6, 5, 4, 3, 2, 1, 0, 11 or 12, a circuit is completed as follows: Assuming, for example, that a hole occurs in the 9 position (at which moment magnet 48 is in line with latch 50 of the 9 counter), from positive line 25, contacts 31, wire 40, commutator brush 37a, common conductor 37, 9 segment 36, brush 36a, wire 41, card lever contacts 32c, roller 24, 9 hole in the card, brush 12, resistance S8, wire 78, switch 75, center tap of 45 volt battery 76, resistance S17, to negative side of line 26. The flow of current in this circuit brings the center tap of the battery to a potential of +35 volts. The battery voltage from the center tap to its upper terminal is 22.5 volts, so the potential at the three 2-megohm resistors S12, S13 and S14 is about 12.5 volts. These resistances are in series with amplifier vacuum tubes 77 of the type 25L6 and, since all negative potential has now been removed from the grids of these tubes, current may flow freely to the counter magnet 48, through parallel circuits traceable from negative line 26, cathodes of the tubes 77, plates of the tubes, wire 81, magnet 48, wire 40, contacts 31 to positive line 25. The connections to magnet 48 are made through a suitable slip ring and brush device designated 80 generally in Fig. 2, from which wires extend through a bore in shaft 45 to the magnet.

Energization of magnet 48 will thus cause a unit to be added in the 9 counter. The circuit holds only for the duration of the card brush contact through the perforation in the card and, as the brush rides out of the hole, the control grids of the tubes resume a negative potential interrupting current to the magnet. The tube grids are normally maintained at a 45 volt negative potential relative to the cathode by means of resistance S17, the battery and resistors S12, S13 and S14. The tube filaments are connected in series through a circuit from positive line 25, resistor S18, filaments of the three tubes 77, to negative line 26 to heat the cathodes.

The screen grids of tubes 77 are connected to the positive side of line through resistances S9, S10, S11 and S19. This positive potential accelerates the flow of electrons from cathode to plate and resistor S19 serves as a protective resistor for the screen grids should the plate voltage be removed. S19 is chosen to give 200 milliamperes current through counter magnet 48 as a static condition. However, the two 100 mfd. condensers 82 connected between the tube side of resistor S18 and negative line 26 serve to maintain the counter magnet current at considerably above 200 milliamperes. The charge in the condensers maintains a high voltage on the screen grids during short drops in the line voltage. During longer line voltage drops, the machine speed reduces so that proper operation is assured at reduced magnet current. Should the machine stop in a position which gives an impulse to the counter magnet circuit, the charge in the con-

densers will bleed off until equilibrium is established at a lower voltage and, therefore, a safe current for the tubes and counter magnet.

As soon as the machine operation is resumed 5 the condensers 82 charge to their original voltage and the impulse current to the magnet is again increased. Thus, by means of the condensers, the screen voltage is changed so as to give high counter magnet current for short impulses 10 and low magnet current for long impulses. Resistors S9, S10 and S11 all serve to isolate the screens, preventing parasitic oscillations.

There are twelve segments 36 on the distributor 35 as stated, and these correspond to the twelve 15 hold positions in the card column and are contacted in order by brush 36a, so that the occurrence of a hole in any of these positions will cause energization of magnet 48 to add a unit in the related counter.

20 *Reject count circuit.*—If no hole is sensed in the card column traversed by brush 12, the relays R5 and R7 will not be energized at the time segment 39 designated RE contacts brush 39a, and a circuit will be completed from line 25, contacts 31, 25 wire 40, brush 37a, conductors 37, 38, segment 39 (RE), brush 39a, wire 83, card lever contacts 32b, contacts R7a, resistance S7, wire 78, switch 75, center tap of battery 76, resistor S17 to negative line 26. This circuit causes operation of 30 tubes 77 in the same manner as when a card hole is sensed, to energize magnet 48 when it is in line with the reject counter designated RE in Fig. 5.

This reject circuit is not completed if a hole 35 had previously been sensed by brush 12, inasmuch as the sensing of the hole will have energized relay R7 and segment 38 of the distributor 35 will have held relay R7 energized until slightly after brush 39a has passed the RE segment 39. Accordingly, contacts R7a would be open during the 40 reject counter operating time.

45 *Total count circuit.*—As brush 39a now engages the segments 39 designated MT, IT and GT, a circuit is completed through each of these segments and traceable as for the reject count circuit to add a unit into each of the three counters similarly identified in Fig. 5. Thus, after a group of cards has been run through the machine and sorted into separate numerical groups, the ring of counters will contain settings representing the 50 number of cards contained in the related sorting pockets and the total number of cards fed.

55 *Printing operation.*—Each counter is provided with numeral wheels 72 (Fig. 4) which in well known manner are displaced during the counting operations. As already mentioned, the sixteen counters are supported on drum 58 whose flange is provided with a notch 84 (Figs. 3 and 5) normally engaged by a detent 85 to hold the drum in position. Upon inward pressing of Print button 86, slide 87 moves to the right as viewed in Fig. 3, and through pin and slot connection 88 rocks lever 89 clockwise to rock rod 90, to which there is secured an arm 91 (Fig. 5). This arm has pin and slot connection 92 with detent 85 which in turn is loosely fitted on rod 90, so that through a screw 93 in the detent 85 the latter may be adjusted in its stopping position. A spring 94 serves as a shock absorber when detent 85 drops into notch 84 during the clockwise rotation of drum 58.

60 Referring to Figs. 2 and 3, drum 58 has secured thereto a gear 95 meshing with a gear 96, on a stud 97 to which there is fastened a hand lever 98. With Print button 86 depressed, the oper-

ator will turn lever 98 through two complete revolutions in a counterclockwise direction as viewed in Fig. 3, so that drum 58 and the counters thereon make a full revolution during which each counter will in turn pass through the printing position opposite platen 99. The platen 99 is supported in a frame comprising side arms 100 (see Fig. 2) pivoted on a rod 101 and urged clockwise by a spring 102. An adjustable eccentric pin 103 limits the movement of the frame and, when drum 58 is in its latched position, a block 104 thereon engages and holds the frame slightly away from its limit stop 103.

The record tape 106 is threaded from a supply roll 107 around guide roller 108 and platen 99 as shown in Fig. 7 and a thin leaf spring 109 (see also Fig. 2) is provided to press the paper against the platen. As the drum 58 rotates, the block 104 releases the print frame and the platen 99 and tape move into the path of movement of the print wheels 72 and, as each set of wheels passes the platen, the frictional engagement of the wheels with the tape will cause the tape to move therewith as the wheels effect an impression on the tape. Just prior to the arrival of a counter at the printing position, its wheels 72 pass over an inking roller 110 which is saturated through a wick extending into a well 111.

Thus, after a revolution of drum 58 in a clockwise direction, a section of tape 106 will have been advanced as shown in Fig. 1. The operator may then draw it still further and tear the section off against the serrated cutting edge 112. Fig. 1 shows a tape section wherein the five left hand columns show the amounts set in the sixteen counters and an extra column of designations identifies the particular counters. These designations are printed from wheels 72a (Figs. 2 and 4) coaxial with wheels 72 and presettable in accordance with desired designations.

Resetting operation.—Each of the counters is provided with a gear 113 (Figs. 2 and 4) which in the case of all but the RE, MT, IT and GT counters is fixed on the countershaft and rotation of this gear will zeroize the counter in the well known manner. In the case of the four other counters, the gear 113 is loose on the countershaft and has adjacent to it a collar 114 which is secured to the shaft and which has a threaded stud 115 rotatable by a hand wheel 116 to couple the collar and gear. When the parts are uncoupled as in Fig. 5, a spring member 117 holds wheel 116 against rotation.

All the gears 113 mesh with a ring gear 118 (see Fig. 5), which ring gear is mounted for rotation on drum 58 so that, if gear 118 is rotated, the gears 113 will be driven to reset their respective counters, and in the case of the four special counters this resetting is selective, depending on whether the collar 114 and gear 113 in such positions have been preliminarily coupled. Fig. 1 shows the coupling wheels 116 in the position they occupy when drum 58 is in its latched position, wherein the wheels are accessible for adjustment.

The manner in which ring gear 118 is rotated is as follows: With drum 58 in latched position, gear 113 of the 8 counter is adjacent to a mutilated gear 120 (Figs. 2 and 5) secured to a shaft 121 whose opposite end carries lever 122 (Figs. 1 and 3). A notched disk 123 engaging a pin 124 in reset slide 125 normally holds the shaft 121 against rotation. Upon depression of Reset button 126, pin 124 releases disk 123 and lever 122 may then be rotated to turn shaft 121 and

through gear 120 the gear 113 of the 8 counter turns ring gear 118, whereupon all other gears 113 are rotated to reset their respective counters.

Referring to Fig. 3, slides 87 and 125 both have an extension 127 which, when either slide is actuated, will engage and open contacts 31 to prevent operation of the card feeding mechanism during a print or reset operation. Slide 125 has a lever 128 pivoted thereon, whose upper end has pin and slot connection 129 with slide 87. This lever coacts with a fixed stud 130 (see Fig. 2) so that, when either slide is moved, the midpoint of the lever 128 will be advanced up to stud 130 and, if the other slide is then moved, stud 130 acts as a fulcrum for lever 128 and said lever is rocked to return the first slide.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a machine of the class described, a plurality of counters, a common actuator therefor, a plurality of elements, one for each counter, for connecting the related counters to said actuator, a latch for each element, said latches being arranged in a circle and lying in a common plane, a magnet, means for continuously moving said magnet in a circle and in a plane parallel to the plane of said latches to pass said latches in succession, energization of said magnet when adjacent to any latch causing an operation of said latch by magnetic attraction to release the related element, means effective upon said release to cause the element to connect the related counter to said actuator, and means for causing energization of said magnet during its movement to operate any one or more latches.
2. In a machine of the class described, a plurality of counters arranged in a circle about a common axis, a counterbalanced magnet and supporting means therefor rotating continuously around said axis to pass the counters in succession, a continuously rotating cam coaxial with the counters and magnet, normally ineffective connections between the cam and counters, and means operative upon energization of said magnet when it is opposite any counter for rendering said connections effective between the cam and said counter whereby the cam will actuate the counter.
3. In a machine of the class described, a plurality of counters arranged in a circle, a plurality of actuating elements also arranged in a circle opposite related counters, each element normally being in an inactive position and movable therefrom to an active position, a continuously rotating arm, selecting means on said arm movable in a circle to pass said elements in succession, means operative while the arm is in motion for causing said selecting means to selectively release one or more actuating elements for movement to their active positions, means acting upon and through the released elements to actuate the related counters.
4. In a machine of the class described, a plurality of counters arranged in a circle, a common actuator, a plurality of actuating elements, one

for each counter, arranged in a circle, each operable to connect its related counter to said common actuator, a latch for each element normally holding the related element out of connecting engagement with the actuator, a continuously 5 rotating arm, a magnet on said arm moving in a circle to successively pass said latches, means for momentarily energizing said magnet during the rotation of said arm, when the magnet is in line with any latch to magnetically attract the latch 10 and release the related element to effect connection between the related counter and said common actuator.
